UNITED STATES PATENT OFFICE.

AUGUST SZARKA, OF VESTABURG, PENNSYLVANIA.

CAR-COUPING.

1,294,724.

Specification of Letters Patent. Patented Feb. 18, 1919

Application filed September 23, 1918. Serial No. 255,216.

To all whom it may concern:

Be it known that I, AUGUST SZARKA, a subject of the King of Hungary, residing at Vestaburg, in the county of Washington and State of Pennsylvania, have invented new and useful Improvements in Car-Couplings, of which the following is a specification.

My invention relates to car-couplers of the link type.

10 The object of this invention is to provide means whereby the coupling of cars may be effected automatically and whereby the coupling-link may be readily released without danger to the man operating the same.

15 On the accompanying drawings, Figure 1 is a vertical longitudinal view of a coupling taken on the line I—I of Fig. 2 and embodying my invention; Fig. 2, a top plan view of my invention; Fig. 3, a horizontal longitudinal section taken on the line III—III of Fig. 1; and Fig. 4, a transverse section on the line IV—IV of Fig. 1.

On the drawings, 1 designates the coupler body which is provided with a longitudinal opening, the inner portion thereof being shaped transversely in the form of a cross having right angles. The two lateral members of the cross-shaped opening are marked with the numeral 2 and the two vertical members thereof with the numeral 3. The front portion of the said opening is rectangular in cross-section and flares forwardly from the front end of the said cross-shaped portion.

35 A recess 4 is provided in the top of the body 1 just above the forward end of the cross-shaped portion of the said opening. The central portion of this recess intersects the upper portion of the upper member 3.

40 A pivoted latch 5 is inserted downwardly through the recess 4 and has the lateral bearings 6 resting in the bottom of the recess 4 at the sides thereof. This latch 5 extends through the top member 3 and in the bottom member 3 and lies between the lateral members 2. The recess 4 is covered by a plate 7 removably secured in a recess in the top of the body 1.

The body 1 is provided with a recess 8 in its bottom just forwardly of the latch 5. A flat spring 9 is secured in a recess in the bottom of the body 1 and has secured to the forward end thereof the catch or detent 10 which occupies the recess 8 and has its upper 55 surface beveled to correspond with the slant of the flaring portion of the body opening.

11 is a transverse shaft which passes through the body 1 at the rear of the detent 10. To this shaft I secure two forwardly projecting arms 12 working in recesses 13 in the body 1 at opposite sides of the lower member 3 of the body opening. The forward ends of these arms 12 lie upon the lateral projections 14 of the detent 10. 15 represents a handle for rotating the shaft 11. 60

In order to couple together two cars, one of the cars is provided with the coupling link 16 shown on Fig. 1. The parts of the coupler being as shown on the drawings, the link 16 enters the flaring end of the coupler opening and is guided by the walls thereof into the horizontal members 2 of the cross-shaped opening of the body. The forward end of the link 16 first engages the forward side of the latch 5 and swings the same rearwardly in the upper member 3 until the latch drops into the opening in the link. The latch then swings forwardly into engagement with the detent 10 and serves as a coupling pin to prevent the withdrawal of the 70 link 16 from the body 1. When it is desired to release the link it is only necessary to operate the handle 15 in the proper direction to cause the arms 12 to press the detent 10 downwardly below the lower end of the latch 75 5, whereupon the link 16 may be withdrawn, causing the latch 5 to swing forwardly in the upper member 3.

I prefer to have the pivot-bearings of the latch a little forwardly of that side of the 90 latch which faces the front or flaring opening in the body 1 so that, when the detent 10 is pressed down below the latch the latter will automatically swing forwardly over the top of the detent, thereby preventing the detent from coming up in front of the latch. I provide the forward side of the lower end of the latch with a projection 5^a which insures that the latch will keep vertical when engaged with the detent. 95

The detent 10 may be made slideable on the front end of the spring 9 by providing the latter with a lug 9^a which extends up into a recess in the bottom of the detent. The lug is provided with a slot 9^b through which a 105 pin 9^c extends to secure the detent to the spring. The slot 9^b permits the detent to slide on the pin 9^c and engage the forward wall of the recess 8, so that heavy shocks on the detent 10 and spring 9 may be greatly lessened. 110

I prefer to make the side-members 2 some-

what inclined outwardly and rearwardly for a short distance from the region of the detent 10 as shown at 2^a to provide lateral play for the link when the car goes around sharp curves and the link is in the rear part of the opening in the coupler body.

I claim—

1. In a car-coupler, a body having a longitudinal opening, a link receivable into the opening, a pivoted latch arranged to swing in the opening and to be pushed rearwardly by the link entering the opening and to drop into the opening in the link, a detent in an opening in the body to prevent the catch from swinging forwardly, a swinging plate supporting the detent, means permitting the detent to slide on the plate and into engagement with the front wall of the last-named opening, and means for making the detent ineffective.
2. In a car-coupler, a body having a longitudinal opening, a link receivable into the opening, a pivoted latch arranged to swing in the opening and to be pushed rearwardly by the link entering the opening and to drop into the opening in the link, a detent to prevent the catch from swinging forwardly, and means for making the detent ineffective, the said opening flaring rearwardly and laterally beyond the detent to permit the inner end of the link to swing horizontally when pushed in the rear portion of the opening.
3. In a car-coupler, a body having a longitudinal opening, a link receivable into the opening, a pivoted latch having lateral pivot bearings and arranged to swing in the opening and to be pushed rearwardly by the link entering the opening and to drop into the opening in the link, a detent to prevent the

catch from swinging forwardly, means for 40 making the detent ineffective, the said body having open-ended recesses in its top side to receive the pivot bearings of the latch, and a removable cover for the recess.

4. In a car-coupler, a body having a longitudinal opening with its front portion tapering rearwardly and its rear portion cross-shaped, a link receivable into the lateral members of the cross-shaped portion of the opening, a pivoted latch arranged to swing 50 in the vertical members of said cross-shaped portion of the opening and to be pushed rearwardly by the link entering the opening and to drop into the opening in the link, a detent to prevent the catch from swinging forwardly, and a rotary shaft provided with 55 arms to engage and depress the detent below the end of the latch.

5. In a car-coupler, a body having a longitudinal opening with its front portion tapering rearwardly and its rear portion cross-shaped, a link receivable into the lateral members of the cross-shaped portion of the opening, a pivoted latch arranged to swing 60 in the vertical members of said cross-shaped portion of the opening and to be pushed rearwardly by the link entering the opening and to drop into the opening in the link, a spring plate secured to one side of the body, a detent carried by the spring plate and 65 pressed thereby into the path of the latch to prevent the catch from swinging forwardly and means for making the detent ineffective.

Signed at Pittsburgh, Pa., this 11th day 75 of September, 1918.

AUGUST SZARKA.
